US00D912050S

(12) **United States Design Patent** (10) **Patent No.:** **US D912,050 S**
(45) **Date of Patent:** **** Mar. 2, 2021**

(54) **KEYBOARD**

(71) Applicant: **Shenzhen Riitek Technology Co., LTD.**, Guangdong (CN)

(72) Inventors: **Xianyong Pang**, Shenzhen (CN); **Junkui Chen**, Shenzhen (CN)

(73) Assignee: **Shenzhen Riitek Technology Co., Ltd.**, Guangdong (CN)

(**) Term: **15 Years**

(21) Appl. No.: **29/640,012**

(22) Filed: **Mar. 11, 2018**

(51) LOC (13) Cl. **14-02**

(52) U.S. Cl.

USPC **D14/391**

(58) **Field of Classification Search**

USPC .... D14/315-327, 391-399, 455-457, 247, D14/346, 203.4, 203.6, 345, 477, 507, D14/509; D18/1-2, 4.1-4.6, 7, 11; 235/145 A, 145 R; 341/22-23; 345/104, 345/156, 168-169, 173; 361/679.08, 361/679.09, 679.11, 679.26, 679.27; 708/142, 146

CPC B41J 5/00; B41J 5/10; B41J 5/12; F16M 11/10; G06F 3/0219; G06F 3/02

(57) **CLAIM**

The ornamental design for a keyboard, as shown and described.

DESCRIPTION

FIG. 1 is a perspective view of the keyboard showing my new design;

FIG. 2 is a front view of the keyboard;

FIG. 3 is a rear view of the keyboard;

FIG. 4 is a left view of the keyboard;

FIG. 5 is a right view of the keyboard;

FIG. 6 is a top view of the keyboard; and,

FIG. 7 is a bottom view of the keyboard.

The broken lines show portions of the keyboard which form no part of the claimed design.

1 Claim, 7 Drawing Sheets
